(57) **CLAIM**

The ornamental design for a mobile phone case, as shown and described.

DESCRIPTION

FIG. 1 is a front perspective view of a mobile phone case showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded front perspective view of the mobile phone case thereof; and,

FIG. 10 is a partial enlarged view of the selected portion 10 in FIG. 1.

The dash-dash broken lines shown in the drawings depict portions of the mobile phone case that form no part of the claimed design. The dot-dash broken line circles and connected wavy lines in FIGS. 1 and 10 are included for the purpose of delineating the partial enlarged view and form no part of the claimed design.
